CLAIM

The ornamental design for a pet feeder as shown and described.

DESCRIPTION

FIG. 1 is a top, front perspective view of a pet feeder showing the first embodiment of my new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a bottom, rear perspective view thereof; and,

FIG. 9 is a top, front perspective view of a pet feeder showing the second embodiment of my new design, and the difference is only in the control button.

1 Claim, 9 Drawing Sheets
